UNITED STATES PATENT OFFICE.

HERMAN C. PRIEBE, OF BRADFORD, ILLINOIS, ASSIGNOR OF ONE-HALF TO
FRANK J. REICHMANN, OF CHICAGO, ILLINOIS.

DRAFT-RIGGING.

SPECIFICATION forming part of Letters Patent No. 703,607, dated July 1, 1902.

Application filed December 12, 1901. Serial No. 85,632. (No model.)

To all whom it may concern:

Be it known that I, HERMAN C. PRIEBE, a citizen of the United States, residing at Bradford, in the county of Stark and State of Illinois, have invented a new and useful Improvement in Draft-Riggings, of which the following is a specification.

My invention relates to an improved construction of draft-rigging for freight-cars.

10 My object is to provide a draft-rigging of improved construction which will possess certain advantages over the draft-riggings hitherto provided upon freight-cars in the matter of strength, durability, and other features, as 15 hereinafter set forth.

In the drawings, Figure 1 is a broken sectional plan view taken on line 1 in Fig. 3 through the center and end sills of a car; Fig. 2, a cross-section on irregular line 2 in Fig. 1; 20 Fig. 3, a section on line 3 in Fig. 1 with a part broken away to display details of construction; Fig. 4, a broken elevation, and Fig. 5 a broken plan view of draft-plates forming part of the rigging construction.

25 A A are the longitudinally-extending center sills of a car-frame; B, one of the end sills; C, a dead-wood, and D the transom.

30 E E are draft-plates which may extend the full length of the car. The plates E are angular in cross-section, being formed with the face portions a, upper narrow spacing-flanges b, and lower wide attaching-flanges c. The drawings show the construction at one end of the car only; but it is to be understood that 35 the draft-rigging is the same at each end of the car. The end sill B and dead-wood or buffer-block C are cut away at the center of their under sides, forming an opening or socket d for the draw-bar F, which may slide

40 over the draw-bar carry-plate e, bolted against the under side of the dead-wood. The flanges b c are cutaway toward the ends of the draft-plates, and the face portions a are rendered narrower to pass through the socket d. The 45 plates E extend along the inner sides of the center sills A, the free edges of the flanges b resting against the faces of the sills and the flanges c resting against the under sides thereof. The draft-plates are held securely

50 in place by means of horizontal bolts x and vertical bolts x', which extend through the

sills. The reduced end portions a' of the draft-plates extend through the end sill and dead-wood at opposite sides of the socket d and are upset at the outer ends over the dead-wood to aid in holding the dead-wood in place and aid the same in sustaining the draw-bar F. In the draft-plates are coincident sockets f, which may be formed by cutting or stamping the metal. The sockets extend from near 55 the tops of the plates out through the bottoms of the latter. Between the faces a and sills A are fillers G, of wood or other suitable material, cut away to receive the socket portions f of the draft-plates. Secured to the inner 60 end of the draw-bar by means of bolts x² is a stirrup-frame H, containing rigid partitions or cross-plates H' H², securely held in place. The plates or blocks H' H² may extend at their 65 opposite edges into sockets g in the sides of the stirrup-frame and be further held in place by the transverse bolts x³. They register normally with the flat spaces a² a² between sockets f, as shown, and exactly fill out the width of those spaces. Normally the inner end F' 70 of the draw-bar registers with the forward edges of the first pair of companion sockets f, and the inner side of the end of the stirrup-bar H registers with the rear edges of the last pair of companion sockets f. Thus three 75 pockets I I' I² are formed in the stirrup-frame, as shown. In these pockets are the short coiled springs K K' K², bearing at opposite ends against follower-plates L, L', L², L³, L⁴, and L⁵, as shown. The follower-plates fit 80 loosely at their upper and lower edges in the stirrup-frame and at their sides project into the sockets f, which at their edges form shoulders or stops. The construction, as will be 85 seen, is such that the follower L is pressed 90 against the forward edges of the first sockets f, the follower L' against the rear edges of the second sockets f, the follower L² against the forward edges of the third sockets f, the follower L³ against the rear edges of the 95 fourth sockets f, the follower L⁴ against the forward edges of the fifth sockets f, and the follower L⁵ against the rear edges of the last sockets f.

When the draw-bar is drawn in the outward direction, the parts H' H² and end of the stirrup-bar bear against the followers

$L' L^3 L^5$ and compress the springs $K K' K^2$ simultaneously, the follower-plates $L L^2 L^4$ being held against forward movement from normal positions by their engagement with the forward edges of the sockets in which they rest. When the draw-bar is pushed inward, the end F' thereof and parts $H' H^2$ bear against the follower-plates $L L^2 L^4$ and compress the springs $K K' K^2$ simultaneously, the follower-plates $L' L^3 L^5$ being held against backward movement from normal position by the sockets which they engage. Secured by bolts against the under side of the draft-plates are base-plates M , which close the lower ends of the sockets f and prevent the follower-plates from dropping out. At the transom D the draft-plates are provided with notches α^3 , which by fitting over and engaging the transom-bar materially strengthen the car structure.

The advantages of my improved draft-rigging over the draft-rigging in common use are briefly the following: The draft-rigging is mounted between the center sills and not below them. This permits the sills, and consequently the floor of the car, to be lower by at least a foot than is usual in freight-cars as commonly constructed. The draft-plates are applied and the sockets f produced without notching or cutting away the center sills, and thus weakening them. When the draft-plates extend from end to end of the car, as shown, they greatly reinforce the center sills and also the dead woods or blocks at the ends of the car. The springs in practice may be permitted to compress about two inches, and as soon as the springs are exhausted the strain is taken up by the engagement of the follower-plates with the ends of the sockets. This relief of pressure against the springs prevents their breaking under the crushing strain, such breaking being frequent in the constructions hitherto commonly employed. As the resistance of all the springs is at once brought to bear against movement of the draw-bar in either direction, the travel of each draw-bar may be limited to about two inches at each end of the car, and this, it is found in practice, will contribute all the resilience necessary or desirable to prevent undue shock against the car-timbers. It has been usual hitherto to permit the draw-bars to travel, as a rule, about five inches at each end of the car, which in a long train makes a great difference in the initial movement of the cars or stoppage thereof or change of speed. The limitation upon the movement of the draw-bars which my invention effects greatly decreases the danger to trainmen be-

tween cars and also the danger to stock and breakable merchandise carried by the cars.

When the car is constructed with draft-timbers beneath the center sills or in the place of the center sills shown, my improved draft-rigging may be secured thereto instead of directly to the sills, and while I prefer to construct my improvements throughout as shown and described they may be variously modified in the matter of details without departing from the spirit of my invention as defined by the claims.

What I claim as new, and desire to secure by Letters Patent, is—

1. In a draft-rigging for attachment between the center sills of a freight-car, comprising, in combination, draw-bars extended through openings in the front sills and dead-woods, flanged draft-plates secured to the inner sides of the center sills said draft-plates extending the full length of the car and having reduced ends passed through the openings in the front sills and dead-woods to reinforce the latter, and yielding connections between the draw-bars and draft-plates. 75

2. In a draft-rigging, the combination with a draw-bar of a stirrup-frame thereon having a series of pockets formed by cross-plates having socket connection with the stirrup-frame, two follower-plates and a separating buffer-spring between the said plates in each pocket, 80 draft-plates secured to the inner sides of the center sills on opposite sides of the stirrup-frame and having coincident sockets, registering with said pockets, into which the follower-plates extend at opposite sides, the sockets presenting stops to limit movement of the follower-plates, substantially as described. 90

3. In a draft-rigging, the combination of the draft-plates secured to the inner sides of the center sills and having sockets, the draw-bar, stirrup-frame on the draw-bar, pockets in the stirrup-frame formed by cross-plates having socket connection with the stirrup-frame, follower-plates in the pockets extending at opposite sides into said sockets, simultaneously-acting buffer-springs in the pocket between the follower-plates and operating normally to press the follower-plates against the ends of the pockets and sockets, the said sockets presenting shoulders which limit the movements of the follower-plates in each direction and relieve the pressure against the springs when compressed, substantially as described. 100 105 110
